Patented Mar. 8, 1921.

UNITED STATES PATENT OFFICE.

EDWARD J. BRADY, OF PHILADELPHIA, PENNSYLVANIA, ASSIGNOR TO THE U. G. I. CONTRACTING COMPANY, OF PHILADELPHIA, PENNSYLVANIA, A CORPORATION OF DELAWARE.

HEATING-VALUE INDICATOR FOR ILLUMINATING-GAS.

1,370,945.

Specification of Letters Patent.

Patented Mar. 8, 1921.

Application filed July 29, 1919. Serial No. 314,145.

To all whom it may concern:

Be it known that I, EDWARD J. BRADY, a citizen of the United States, residing at Philadelphia, in the county of Philadelphia, 5 and State of Pennsylvania, have invented a new and useful Heating-Value Indicator for Illuminating-Gas, of which the following is a specification.

The present invention is based on my discovery that the value of the ratio of air to gas both measured by volume in a mixture of air and illuminating gas as the luminous tip disappears from a flame, supplied by the mixture, is a measure of the heating value of the illuminating gas, and the invention consists broadly in the provision of ways and means for the practical and commercial utilization of this discovery for the rapid and inexpensive determination of the 20 heating value of illuminating gas.

The principle upon which the invention is based is the following: If ordinary illuminating gas (containing considerable percentage of hydrocarbons), without any air pre-mixed, is supplied to, for example, a round orifice burner, the flame will not be blue but will be very large, luminous and even smoky. If now some air be admitted pre-mixed with the gas, this luminosity of the flame will decrease, and if the quantity of air pre-mixed with the gas is further increased, the luminosity will gradually decrease until the flame is nearly all blue, having merely a luminous tip in its center; a small further increase in air will extinguish even this luminous tip. The ratio, by volume, of this pre-mixed air to the gas at this latter moment of disappearance of the luminous tip is found, by experiment, to be an accurate index of the heating value of the gas. As will be seen from the following description, this change of ratio of pre-mixed air and gas can be made in a variety of ways, for example, automatically and gradually, and a scale, prepared by standardization of the apparatus against a standard form of calorimeter can be used to indicate, at the exact moment of the disappearance of the luminous tip, the heating power

of the gas, so that the invention is not intended to be limited in form of embodiment of the instrumentalities and means employed.

The invention will be claimed at the end hereof, but one embodiment of it, selected from other embodiments, will be first described in connection with the accompanying drawings forming part hereof and in which—

Figure 1, is an elevational view, principally in section, of one form of instrument embodying a combination of elements illustrative of instrumentalities adapted for the utilization of my discovery, and

Fig. 2, is a similar view illustrating a modification.

Referring to Fig. 1, the body of the apparatus consists of two concentric closed tubes 1 and 2, as of glass; within the interior tube 2, is a hollow, closed, inverted conical tube 3, as of metal. By means of the "aspirator" 4, the apparatus is first completely filled with water; then by means of this same aspirator, and the operating of the proper admission cocks 5 and 6, air is drawn into the outer space *a*, and gas into the interior space *b*, the cocks being so arranged that there is no mixture whatever of this air and gas in thus filling the apparatus. The openings 7, at the bottom of the vessel 80 put the gas and air spaces or chambers into communication, but simply for the admission of water from one to the other. By means again of the aspirator 4, the air and gas are put under pressure ready for discharge to the burner. A proper adjustment of the barrel cock 8, at top of the apparatus now puts the apparatus in readiness for the discharge of air and gas to the burner 9. Because of the inverted cone 3, in the interior glass tube 2, it will readily be seen that whereas the air forced out will be exactly proportional to the rise of the water in the apparatus, this will not be true of the gas, this latter will continually decrease in quantity, or the ratio of air to gas will continually change. The gas and air mixture then passes to the bulb 10, on top of

the apparatus, where a more thorough mixture takes place. This mixture of air and gas is then finally discharged and burned at the burner 9.

- 5 As indicated in the opening description above, as the water rises in this apparatus the flame of the burner will continually change, and finally even its luminous tip will disappear. At the moment of disappearance the water is stopped flowing by closing cock 13, and the position of the water level is read upon the calibrated scale 11, at the side, which itself, or upon reference to an accompanying table, will at once indicate the heating power of the gas.

In the embodiment of the invention above described the burner 9, is removed and the connection 12, is attached to a supply of the illuminating gas to be tested while the space 20 or chamber in the tube 2, is being filled with gas as has been described. By this arrangement one opening in the tube 2, is made to serve both as an inlet for gas and as an outlet for both air and gas, as determined by the position of the barrel cock 8.

In Fig. 2, the conical body 3, is omitted and the shape of the walls of the tube 2^b, performs the same function as the body.

The expression illuminating gas is intended to refer not only to illuminating gas or gases in the generally accepted meaning of that term, but also to combustible gas or gases having sufficient illuminating power for producing the luminous tip.

35 While the determination of the heating value of illuminating gas by the described disappearance or absence of the luminous tip is a very important part of my invention, still I do not limit my invention in apparatus to that method of use, but claim the same for all the applications in which it is useful and which have to do with the determination of the heating value of combustible gas, whether by the disappearing tip method or otherwise.

It will be obvious to those skilled in the art to which the invention relates that modifications may be made in details of construction and arrangement and in the form of 50 the instrumentalities employed without departing from the spirit of the invention which is not limited as to those matters or otherwise than as the prior state of the art and the appended claims may require.

55 I claim:

1. A heating value indicator for gas comprising the combination of a burner having a tip and a fuel inlet and closed to the atmosphere between the inlet and tip and adapted to provide a flame at its top only, means for supplying a pre-mixture of air and gas at the fuel inlet in changing ratio, and provisions for ascertaining the air and gas ratio at which the luminous tip ceases

to exist in the flame at the top of the burner, 65 substantially as described.

2. A heating value indicator for illuminating gas comprising the combination of a burner for burning at its top a pre-mixture of air and illuminating gas, mixing 70 means for automatically pre-mixing the air and gas in changing ratio to cause the luminous tip to disappear from the burner flame, and devices for ascertaining the air and gas ratio at which the luminous tip 75 ceases to exist and which indicates the heating value, substantially as described.

3. A heating value indicator for illuminating gas comprising in combination an air supply chamber of uniform cross-section, 80 a gas supply chamber of varying cross-section, means for establishing and varying a common fluid level in said chambers, a burner supplied from said chambers, and devices for indicating the fluid level, substantially as described.

4. A heating value indicator for illuminating gas comprising in combination air and gas chambers of differing ratio of cross-section, a burner connected to said chambers, 90 and means for raising a water level in said chambers, substantially as described.

5. A heating value indicator for illuminating gas comprising in combination air and gas chambers of differing ratio of cross-section, a burner connected to said chambers, 95 means for raising a water level in said chambers, and a water level scale.

6. A heating value indicator for illuminating gas comprising in combination air 100 and gas chambers of which one is internally uniform and of which the other is internally tapering, fluid-level connections for said chambers, and a burner supplied from said chambers, substantially as described.

7. A heating value indicator for illuminating gas comprising in combination closed tubes, a conical body in one of the tubes, an aspirator for controlling fluid level in the tubes, a scale, air and gas admission 110 provisions for the tubes, and a burner common to the tubes, substantially as described.

8. In a heating value indicator for gas in combination nested closed tubes of varying ratio cross-section inter-communicating 115 near the bottom thereof, air and gas admission provisions for the tubes, a burner connection common to both tubes, a scale, and an aspirator communicating with the lower portion of one of said tubes.

9. A heating value indicator for gas comprising in combination nested closed tubes of varying ratio of cross-section inter-communicating near the top and bottom thereof and of which one is provided with admission 125 provisions, a valve for the communication near the top of the tubes, a valved terminal connection common to the tubes, a scale, and

an aspirator communicating with the lower portion of one of the tubes, substantially as described.

10. A heating value indicator for gas comprising the combination of a burner having a tip and a fuel inlet and closed to the atmosphere between the inlet and tip and adapted to provide a flame at its top only,

means for supplying a pre-mixture of air and gas at the fuel inlet in progressively changing ratio, and provisions for ascertaining the air and gas ratio at which the luminous tip ceases to exist in the flame at the top of the burner, substantially as described.

EDWARD J. BRADY.
